United States Patent Office.

JAMES S. ATTERBURY AND THOMAS B. ATTERBURY, OF PITTSBURG,
PENNSYLVANIA.

Design No. 4,259, dated July 26, 1870.

DESIGN FOR A LAMP.

The Schedule referred to in these Letters Patent and making part of the same

To all whom it may concern:

Be it known that we, JAMES S. ATTERBURY and THOMAS B. ATTERBURY, of Pittsburg, in the county of Allegheny and State of Pennsylvania, have invented and produced a new and original Design for a Lamp, of which the following is a specification, reference being had to the accompanying drawing making part of this specification, in which—

Figure 1 is an elevation of the lamp.

Figure 2 is a view of the top of the lamp.

Our invention consists of a lamp having a spheroidal bowl, A, surmounted by a collar, a, and con-

nected to a hemispheroidal base, C, by means of a pedestal, B, having a concave outline.

The diameter of the base C is about equal to that of the bowl, and the diameter of the bowl A, taken vertically, is less than its lateral diameter.

We claim as our invention, and desire to secure by Letters Patent—

The design for a lamp herein set forth.

JAS. S. ATTERBURY.

Witnesses: THOS. B. ATTERBURY.
